UNITED STATES PATENT OFFICE.

JOHN G. SNYDER, OF NEW YORK, N. Y.

TIE AND FASTENER.

Application filed September 3, 1925. Serial No. 54,306.

This invention relates to rail ties and fasteners and has for an object to provide an improved construction which embodies a minimum number of parts but which will effectively support a rail and present clamping means for clamping the rail in position.

Another object of the invention is to provide a tie and fastener wherein a reinforcing plate is associated with a tie body having overhanging flanges whereby clips may be used which will interlock with the flanges, the plate and the rail for connecting all of the parts together.

A further object of the invention is to provide a tie and fastener wherein a reinforcing plate is used and also wherein insulating members are provided for insulating the plate and associated parts from the tie.

20 In the accompanying drawings—

Figure 1 is a perspective view of a tie disclosing certain features of the invention, the same being illustrated in connection with one set of clips and a section of rail.

25 Figure 2 is an enlarged sectional view through Figure 1, approximately on line 2—2.

Figure 3 is a sectional view through Figure 2 on line 3—3.

30 Figure 4 is an inverted perspective view of the clip shown in Figures 1 and 2.

Figure 5 is a fragmentary top plan view showing one end of a tie similar to that shown in Figure 1 but illustrating how a 35 reinforcing plate may be used thereon.

Figure 6 is a sectional view through Figure 5 on line 6—6.

Figure 7 is a sectional view through Figure 6 on line 7—7.

40 Figure 8 is a perspective view on a reduced scale, showing the plate illustrated in Figure 5.

Figure 8^a is a slightly modified form of reinforcing plate to that shown in Figure 8.

45 Figure 9 is an inverted perspective view of the clips shown in Figures 5 and 6.

Figure 10 is a fragmentary top plan view similar to that shown in Figure 5 but illustrating a modified form of the invention 50 wherein insulating members are used.

Figure 11 is a sectional view through Figure 10 on line 11—11.

Figure 12 is a sectional view through Figure 11 on line 12—12.

46 Referring to the accompanying drawings

by numerals, 1 indicates a tie which is of the desired length and which is preferably formed with turned down ends 2 and 3 though these ends could be open if desired. The tie 1 is rolled and in the rolling, a depressed U-shaped structure 4 is provided, the same being formed with overhanging flanges 5 and 6 presenting shoulders co-acting with the head 7 of bolt 8. The depending portion 4 in addition presents on the under surface of the tie a reinforcing bead which preferably extends the full length of the tie. When the ends 2 and 3 are turned down, one or more notches 9 are provided in each of the shoulders or flanges 5 and 6 in order that the head 7 may be inserted and the bolt moved over to the desired place. In addition, each of the flanges is preferably provided with a notch 10 on each side of the place where the rail 11 is to be positioned whereby the depending portion 12 of the clip 13 will properly fit into these notches when the clip is in operative position as shown in Figures 1 and 2. The depending portion 12 may be at the end of the clip 13 or set inwardly a short distance from the end as shown in Figure 4. The overhanging portion 14 presents an apron which overlaps part of the shoulders 5 and 6 so that any upward pull on the clamping shoulder 15 will produce a substantially direct longitudinal pull on the bolt 8. It will be noted that the clip 13 is provided with an opening or hole 16 which is positioned so that the head 7 will somewhat underlap the edge of the base of the rail 11, though if desired, the parts could be otherwise positioned. The parts are arranged as just described in order that any strain on the bolt 8 will be substantially longitudinal thereof and, consequently, the bolt will resist to a maximum extent. It will be noted that the shoulders 5 and 6 are thicker than the remaining part of the tie body which is substantially U-shaped in cross section. This is preferable as it presents a stronger shoulder against which the bolt acts, though if preferred, the parts could all be of the same thickness. As the tie is preferably rolled when it is formed, the slot between the shoulders 5 and 6 extends the full length of the tie body and also down over the ends which are preferably bent down or closed.

In the construction shown in Figures 1 to 4 inclusive, an efficient tie and fastener

are presented which may be used for yard purposes or other tracks where a block signal system is not in vogue. When the tie is to be used for a block signal system, 5 some form of insulation must be provided, as for instance, that shown in Figures 10 to 12 inclusive. For some purposes it may be desired to reinforce the tie beneath the rails and when this is the case a slightly 10 modified construction is provided as shown in Figures 5 to 9 inclusive wherein a reinforcing and supporting plate 16 is provided. This plate is provided with openings 17 and 18 which accommodate the respective bolts 15 8 and 8', said bolts also passing through the clips 19 and 20. The tie 1 shown in Figures 5, 6 and 7 is identical with that shown in Figure 1 and will, therefore, need no additional description. The clips 19 and 20 20 are identical but slightly different from that shown in Figure 4 in that a shoulder or offset 21 is provided adapted to press against part of the upper surface of plate 16 so as to firmly clamp the same in place 25 independently of clamping the rail 11. The shoulder 15 in this form of the invention clamps the rail 11 in place and may be positioned to snugly fit against the rail when in 30 operative position or may be spaced slightly therefrom in order to permit what is commonly known as the waving motion of the rail. Regardless of whether or not the shoulder 15 is engaging the rail 11, the shoulder or offset 21 is tightly engaging 35 the plate 16 and continually acts to clamp the same in place whenever the nuts of the respective bolts 8 and 8' are tightened. By this construction and arrangement, the reinforcing structure is provided for the tie 40 body 1 without the necessity of welding, riveting or otherwise securing the same in place except through the action of the respective clips and bolts which act also in the capacity of fastening means for a rail. It 45 will be noted that as the bolts extend through the notches 17 and 18, the plate 16 is prevented any movement longitudinally of the rail or longitudinally of the tie and is firmly clamped in position so that there 50 never will be any loose movement even though a slight movement is permitted in the rail 11.

In Figures 10 to 12 inclusive, a further modified form of the invention is shown to 55 that illustrated in Figures 1 and 5, said modification consisting in the addition of insulation to the structure shown in Figure 5. As indicated in these figures, a plate 22 of any suitable insulation, as for instance, 60 fiber, is arranged under the plate 16 and preferably extends merely to the edge thereof as shown in Figure 12 though it could extend beyond without departing from the 65 spirit of the invention. An insulating member 23 is provided which surrounds the heads

7 of the respective bolts except at two points whereby the head of the bolt cannot engage the depending portion 4 at any point or either of the shoulders 5 and 6. Preferably, a separate insulating member 24 is 70 provided for each of the clips 19 and 20, each of the reinforcing members 24 being provided with a depending portion 25 for insulating the foot or interlocking member 12. It will thus be seen that the bolts and 75 clips as well as plate 16 are all insulated from the tie 1 and as rail 11 rests on plate 16, said rail is also insulated. As the clips are clamped down tightly and also clamp the plate 16 tightly in position, there is no 80 independent movement of the insulation or the parts which come in contact therewith. Consequently, when a train passes over the rail 11, it will merely apply weight but will 85 not produce any friction and, consequently, there will practically be no wear on the insulation. The insulating members 24 may extend beyond the respective clips 19 and 20 as shown in Figure 1 or may extend only 90 to the edge thereof as preferred.

Figure 8^a shows a modified structure to that illustrated in Figure 8. This form of reinforcing plate is shown as a wedge-shaped structure and is used to cant the rail on 95 curves and other places, as desired. It will be noted that this plate is provided with openings on each side in a similar manner to plate 8. This plate may be used either with or without insulation as desired. 100

What I claim is:

1. In a tie and rail fastener, a tie body provided with a depending central portion extending longitudinally of the body and with overhanging flanges forming shoulders with a slot therebetween, said shoulders being thicker than the remaining part of the tie body, each of said shoulders being provided with a notch, a clip formed with a depending portion fitting into said notch and positioned to overlap the base of a rail so as to clamp the same on the tie body, and a bolt having its head interlocking with said flanges, said bolt extending through said clip and acting to clamp the clip in position. 110

2. A rail tie and fastener, comprising a tie body formed with a pair of integral facing shoulders having an open space therebeneath, said shoulders having notches therein, a clip formed with a depending portion fitting into said notches, said clip having a bolt receiving opening, and a bolt extending through said opening for clamping the clip in place, said clip acting to clamp a rail on said tie body, the position of said opening causing the head of the bolt to interlock with said shoulders and to underlap part of the base of said rail. 120

3. In a rail tie and fastener, a tie body adapted to receive a rail thereon, a clip for clamping said rail in position, and a bolt 130

interlocking with the tie body for clamping said clip in position, said clip being formed with a depending portion interlocking with the tie body and with a rearward extending apron extending from said depending portion in a direction away from the rail.

4. A rail tie and fastener, comprising a tie body formed with a depending central longitudinal portion having integral overhanging shoulders, each of said shoulders being provided with a plurality of notches, a clip for each pair of notches, said clips acting to clamp a rail on said tie body, and a reinforcing plate arranged beneath said rail and between said clips, each of said clips being formed with a shoulder engaging part of the upper surface of the plate for clamping the same tightly against the tie body.

5. A rail tie fastener, comprising a tie body having a longitudinal depression in the upper surface and shoulders overhanging said depression, said shoulders being spaced apart, said shoulders being provided with clip receiving notches, a pair of clips for each rail mounted on the tie body, each of said clips having a bolt receiving openings therein, a reinforcing plate arranged beneath said rail, said plate having a bolt receiving opening on each side of the rail, and a bolt for each clip, said bolts interlocking with said shoulders and extending through the openings of the plate and clips for holding the plate in a fixed position independently of the rail and for clamping the clips in position for holding the rail in operative position, each of said clips being formed with a shoulder adapted to engage the plate independent of the rail.

6. In a rail tie and fastener, a tie body formed with longitudinally positioned shoulders formed as part of the upper surface, each of said shoulders being provided with notches, a pair of clips for each rail formed with means engaging said notches, said clips acting to clamp a rail on said tie body, a reinforcing plate arranged between said rail and the body but on the upper surface of the tie body, each of said clips having a shoulder independently engaging part of the upper surface of said plate, said plate having a pair of openings therein and each of said clips having a bolt receiving opening therein, a bolt for each of said clips interlocking with said shoulder and extending through the various openings whereby the clips act to rigidly clamp the plate against movement and also act to hold the rail on the plate.

7. In a rail tie and fastener, a clamping clip comprising a body formed with a depending portion for engaging a tie, a clamping shoulder for clamping a reinforcing plate in position, a rail engaging shoulder for clamping the rail in position, and a bolt

receiving opening for receiving a clamping bolt.

8. In a rail tie and fastener, a tie body formed with facing shoulders in the upper surface having a recess therebeneath, each of said shoulders having a clip receiving notch, a reinforcing plate arranged between said notches, said plate having bolt receiving openings, said plate being adapted to receive and support a rail, a clip adapted to be positioned on each side of said plate for clamping a rail on the plate, said clips having depending portions fitting into said notches, a bolt for each clip, said bolts extending through the openings in the plate and through the clips, and insulating means arranged to insulate the plate, clips and bolts from the tie.

9. A rail tie and fastener, comprising a tie body formed with longitudinal grooves in the upper surface and an integral shoulder overhanging each groove, each of said shoulders being provided with a pair of notches near where the rail is to be placed on the tie, a reinforcing plate arranged between said notches and beneath the rail, said plate having openings on opposite sides and in line with the space between said shoulders, a clip arranged on each side of said rail, each of said clips being formed with a member projecting into the respective notches, and a shoulder resting on said plate, a bolt for each of said clips, said bolts extending through the openings in the clips and the respective openings in said plate whereby when the bolts are tightened the clips will be clamped firmly in place and press tightly against the plate for clamping the same in place while presenting clamping overhanging shoulders engaging the base of said rail, an insulating plate substantially of the same shape as the reinforcing plate arranged between said reinforcing plate and said tie, insulating means arranged between each of said clips and said tie, and insulating means arranged between said bolt and said tie.

10. A rail tie and fastener, comprising a tie body formed with shoulders in the upper surface, a reinforcing plate extending across said shoulders, said plate being formed with openings on opposite sides in line with the openings between said shoulders, an insulating member of the same shape as the plate arranged between the plate and the tie, a pair of clips each formed with a shoulder engaging said reinforcing plate for clamping the same in place, a bolt for each clip for clamping the respective clips in place, said bolts having their heads interlocking with said shoulders, and insulating means arranged between the respective clips and said tie and also between the respective bolts and said tie.

11. A rail tie and fastener, comprising a tie body having shoulders forming part of its upper surface, a reinforcing plate, clamping means acting to clamp said plate and the rail on the plate in operative position, and insulating means arranged between the plate and tie and also between the clamping means and the tie, said clamping means, reinforcing means and plate being removably mounted in position.

12. A tie and fastener for rails, comprising a tie body, a plurality of clips, a fastener plate formed with openings on op-

posite edges, and clamping bolts interlocking with said tie body and extending through said clips and through said openings whereby the clips are firmly held in place and also the reinforcing plate held against movement, each of said clips being formed with an overlapping shoulder fitting against the upper surface of the base of a rail resting on said plate, and a shoulder overlapping said plate for clamping the plate independently of the rail.

JOHN G. SNYDER.
